DESIGN FOR A HAT

Arthur J. Stack, Westport, Conn., and Alys C. Moran, New York, N. Y., assignors to Hat Corporation of America, Norwalk, Conn., a corporation of Delaware

Application June 27, 1941, Serial No. 101,737

Term of patent 3½ years

To all whom it may concern:

Be it known that we, Arthur J. Stack and Alys C. Moran, citizens of the United States, residing, respectively, at Westport, in the county of Fairfield and State of Connecticut, and at New York, in the county of New York and State of New York, have invented a new, original, and ornamental Design for a Hat, of which the following is a specification, reference being had to the accompanying drawing, forming a part thereof, and in which—

Fig. 2 is a side view of the hat shown in Fig. 1. Fig. 3 is a front view of the hat shown in Fig. 1. The hat is characterized by a sidewise slope of the top of the crown; a ribbon about the crown having a bow and a free end at the front of the crown, with the free end draped down forwardly of the crown flatwise onto the brim; a forwardly curving rear crown portion; a front crown portion forming an easily distinguishable angle relative to the front brim portion; a crown approximately twice as broad as high; and a brim approximately as wide as the height of the crown, all as shown.

We claim:

The ornamental design for a hat, as shown and described.
